US00D880130S

(12) **United States Design Patent** (10) **Patent No.:** **US D880,130 S**
Kaiserswerth (45) **Date of Patent:** **** Apr. 7, 2020**

(54) **SOLE**(71) Applicant: **Reebok International Limited**, London
(GB)(72) Inventor: **Alice Kaiserswerth**, Munich (DE)(73) Assignee: **Reebok International Limited**, London
(GB)(**) Term: **15 Years**(21) Appl. No.: **29/681,707**(22) Filed: **Feb. 27, 2019****Related U.S. Application Data**

(63) Continuation of application No. 29/625,560, filed on Nov. 10, 2017, now Pat. No. Des. 841,964.

CLAIM

The ornamental design for a sole, as shown and described.

DESCRIPTION

FIG. 1 is a bottom perspective view of a sole showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show environment that form no part of the claimed design.

The dot-dash broken lines in the figures show boundaries that form no part of the claimed design.

The dot-dot-dash broken lines in the figures and the area(s) within the dot-dot-dash broken lines show portions of the sole that form no part of the claimed design.
